UNITED STATES PATENT OFFICE.

WILLEM ROOS, OF NEW YORK, N. Y.

RUDDER FOR SHIPS.

Application filed June 15, 1925. Serial No. 37,259.

This invention relates to steering means for ships, the general object of the invention being to make the rudder in the form of a vertically arranged roller so that when rotated, 5 it will so act upon the water as to cause the ship to turn in the desired direction according to the direction of rotation of the roller.

Another object of the invention is to provide means for turning the rudder at different speeds so as to control the arc in which 10 the vessel is turned.

With this invention, a ship can be backed or reversed without interference on the part 15 of the rudder and a rudder can be placed at the bow of the boat as well as the stern, which will increase the steering effect.

This invention also consists in certain other features of construction and in the combination and arrangement of the several parts, to 20 be hereinafter fully described, illustrated in the accompanying drawings and specifically pointed out in the appended claim.

In describing my invention in detail, reference will be had to the accompanying drawings 25 wherein like characters denote like or corresponding parts throughout the several views, and in which:—

Figure 1 is a view of a ship provided with a rudder at each end thereof in accordance 30 with this invention.

Figures 2 and 3 are diagrammatic views showing how the rudder acts on the current of water passing the same.

Figures 4, 5 and 6 are diagrammatic plan 35 views showing how the improved rudder acts to steer a vessel.

Figure 7 is a similar view but showing a vessel equipped with two rudders at its stern.

Figure 8 is a sectional view of the means 40 for driving one of the rudders.

Figure 9 is a similar view showing the means for driving another rudder.

Figure 10 is a view of the controlling means.

Figure 11 is a view of the motor generator.

Figure 12 is a diagrammatic view of the circuits.

Figure 13 is a diagrammatic view of the controller arrangement.

Figure 14 is a view of the steering apparatus which includes the regulator and the controller.

As shown in these drawings, the rudder 1 is made in the form of a cylinder or hollow

55 roller which is vertically arranged and is secured to a vertical shaft 2 which is suitably

journaled in the hull of the ship. Figure 1 shows a rudder at each end of the hull, though but one rudder can be used, as shown in Figure 4, or two rudders can be used at the stern 60 of the hull, as shown in Figure 7. A motor 3 has its shaft connected with the upper end of the shaft 2, the motor being supported by the supporting frame 4 which is arranged in the hull of the ship. 65

When the ship is to be turned, current is supplied to the motor so as to rotate the rudder and this rotary movement of the rudder will create a current *a* which will move with the rudder, as shown in Figure 2, so that the 70 current *b* shown by the straight arrows at the top of Figure 2 will strike the current *a* and thus be deflected, as shown in Figure 3. The current at the point A will have its velocity increased, while that at B will have its 75 velocity reduced so that but little pressure will be at the point A, while great pressure will be at point B. Thus the rudder will be forced in the direction of the arrow P, Figure 3, which will cause the ship to turn. 80

Thus it is only necessary to rotate the roller in the proper direction to cause the ship to be turned. Figure 4 shows a ship provided with a single rudder at its stern and rotating in a direction to cause the ship to turn to starboard. Figure 5 shows a ship provided with a rudder at each end with the rudders moving in a direction to cause the ship to turn to starboard. Figure 6 shows a ship provided with a rudder at each end and with both rudders 85 rotating in the same direction so that the ship will move sidewise to the right. Figure 7 shows a ship provided with a pair of rudders at its stern, one on each side of the propeller. 90

Some of the advantages of this invention are as follows:—

Even at the low velocity of the ship, a strong steering power can easily be created by increasing the number of rotations. 100

The current of the water does not constitute any reactionary effect to the rotation of the cylinder.

The rudder offers only a small surface to the waves and thus the danger of damage to the rudder in a storm or heavy sea is minimized. 105

By reversed action of the ship, (when the ship sails backward), the rudder acts just as reliably and effectively, as when running 110 ahead.

If a second rudder is added, the steering

effect will be naturally doubled and the ship possesses with this a reserve rudder whose interference with the motion of the ship is entirely negligible.

5 These two rudders will enable a ship to change its sailing direction transversely, without the ship's body itself being turned in a transverse direction.

10 The attaching of two cylinders at the sides of the screw (one cylinder at each side of the screw) is constructively easy and adds to the hydro-dynamic power.

15 By regulating the number of rotations of the rudder, the turning movement of the vessel can be controlled and while any desired means can be used to rotate the rudder at different speeds, I prefer to use an electric motor for rotating each rudder and the means shown in the drawings for supplying current 20 to the same. These means comprise a motor 5 and generator 6 which are connected by the conductors 7 with the current supply of the ship, a switch 8 controlling the connection. A rheostat or controller 9 controls the flow of 25 current to the motor generator. Conductors 10 connect the generator with the motors 3 of the rudders and the controller 11 and the regulator 12 are located in this circuit. These members 11 and 12 are actuated 30 from the steering wheel 13 through the gear-

ing 14 and the gearing 15 so that they operate in unison and these parts are so arranged that starting from zero, in either direction, the voltage is gradually increased as the steering wheel is moved so that when the rudder is 35 thrown into operation, it will gradually pick up speed and according to the amount of movement of the steering wheel. Thus the ship can be turned on a long arc or a short one, as desired. Indicating means, shown generally at 16, are arranged in the circuits and are placed adjacent the steering wheel, as shown in Figure 10.

What I claim is:—

40 In combination with a ship, a supporting frame therein arranged adjacent one end of the ship, a vertically arranged motor supported by the frame with its shaft extending downwardly, a vertically arranged shaft passing through the lower part of the ship 45 and in alignment with the shaft of the motor, means for connecting the upper end of said shaft with the motor shaft, a vertically arranged roller or cylinder attached to that part of the shaft projecting from the ship and means for supplying current to the motor to rotate the roller or cylinder to steer the ship.

45 In testimony whereof I affix my signature.
WILLEM ROOS.
